UNITED STATES PATENT OFFICE.

HEMAN D. CROOKER, OF ALVIN, TEXAS.

DESIGN FOR A CLOTHES-POUNDER.

SPECIFICATION forming part of Design No. 29,412, dated September 27, 1898.

Application filed August 23, 1898. Serial No. 689,358. Term of patent 14 years.

To all whom it may concern:

Be it known that I, HEMAN D. CROOKER, a citizen of the United States, residing at Alvin, in the county of Brazoria and State of Texas, 5 have invented and produced a new and original Design for a Clothes-Pounder, of which the following is a specification.

This invention relates to a new and original design for a clothes-pounder; and it has for 10 its object to provide a new and original design of this character that shall be both useful and ornamental.

The leading feature of the design resides in a hollow conical body provided at an intermediate point with a downwardly-dished diaphragm, a central longitudinally-arranged tube provided with a conical lower end flared downwardly and projecting through and below the diaphragm, and a flaring pendent circular flange projected downwardly from the diaphragm in a plane between the shell of the body and the conical lower end of the tube. 15

The minor features of the design are the central longitudinally-arranged tube of the body, projected through and above the apex of the body and provided at its extreme upper end with an exterior annular bead or rib, said tube being further provided within the conical lower end thereof with a circular series 20 of openings arranged in a plane above the central portion of the downwardly-dished diaphragm.

Additional minor features of the design are the body, having a circular group of inclined 25 short tapering tubes projecting outwardly therefrom at a point near its apex, said body further having the lower edges of its rim, its pendent circular flange, and the lower conical end of its tube arranged in different horizontal planes. 30

In the drawings, Figure 1 is a perspective view of a clothes-pounder embodying the herein-described design. Fig. 2 is a vertical longitudinal sectional view thereof. Fig. 3 35 is a bottom plan view of the same.

Referring to the accompanying drawings, the numeral 1 designates a hollow conical body provided at an intermediate point with an interior downwardly-dished diaphragm 2, which diaphragm is centrally pierced by the 50 central longitudinally-arranged tube 3. The central tube 3 extends through and above the apex of the body and is surrounded at its extreme upper end by an annular rounded bead or rib 4, while at its lower end said tube 3 has 55 a conical portion 4, flaring downwardly and projecting below the plane of the interior diaphragm 2. The downwardly-flaring conical portion of the central tube 3 is provided therein with a circular series of circular openings 5, 60 which are arranged in a plane above the plane of the central portion of the diaphragm 2. At a point between the conical lower end 4 of the tube 3 and the rim of the body the latter is further provided with a flaring pendent 65 circular flange 6, which projects downwardly from the diaphragm 2 to a point below the lower edge of the conical lower end 4 of said tube. The lower edge of the body and the lower edge of the rim 6 and of the conical end 70 4 of the tube lie in different horizontal planes, as clearly illustrated in Fig. 2 of the drawings.

To complete the design, the body 1 is further provided with an exterior circular group of short tapering tubes 7. The tapering tubes 75 7 are downwardly inclined, and are offset from the body in a circular plane near the apex thereof.

What is claimed is—

The design for a clothes-pounder, herein 80 shown and described.

In testimony that I claim the foregoing as my own I have hereto affixed my signature in the presence of two witnesses.

HEMAN D. CROOKER.
